FIRE ESCAPE

Park Lester Newbold, Cedar Rapids, Iowa

Application March 25, 1941, Serial No. 385,113

1 Claim. (Cl. 228—40)

This invention relates to fire escapes and has particular relation to a combination flexible ladder and bracket for use in escaping from buildings not equipped with attached fire escapes.

One of the grave problems of escaping from the upper stories of houses or other similar buildings when inside stairways are blocked by flames, smoke or in any other manner, is having some way available of reaching the ground in safety.

It is an object of my invention to provide a new and improved flexible ladder of simple and inexpensive construction that will roll up into a small roll.

Another object of my invention is to provide means for holding the flexible ladder away from outside of the wall.

Another object of my invention is to provide means for engaging the ladder to the window sill.

Another object of my invention is to provide means for engaging the rungs to the main supports so that there is flexibility.

Other and further features and objects of the invention will be more apparent to those skilled in the art upon a consideration of the accompanying drawing and following specification, wherein is disclosed a single exemplary embodiment of the invention, with the understanding, however, that such changes may be made therein as fall within the scope of the appended claim, without departing from the spirit of the invention.

Figure 1 is a view in perspective of an escape constructed according to one embodiment of my invention.

Figure 2 is a view in perspective taken at a different angle and illustrating in particular the V brace means for holding the ladder away from the outside wall.

Figure 3 is a view of the split ring arrangement

for engaging a straight rung to the suspension chains. This arrangement holds the chain links in their proper positions on the rung and permits flexibility without binding.

5 Figure 4 is a view of the double V bracket rung showing the split ring means of engaging the rung to the chain link.

Figure 5 is a view of the split ring in open position.

10 Referring now to the drawing a preferred embodiment of my invention includes a ladder indicated generally at 10 and a bracket arrangement indicated at 11. I preferably use chains 12 for the main members of the ladder with rungs 13 extending through the links and held in place by split rings 14. Both side members of the ladder converge together at the top and are engaged to a hook 17 which engages the inside of the window sill or to other anchorage.

15 20 The bracket arrangement 11 by being inserted through links of the supporting chains 12 also serves as the top rung, or where placed, and in use the V shaped points 15 rest against the outside wall 16 holding the ladder at a distance so that in descending ones hands are not subjected to injury by coming in contact with the wall.

25 20 The split rings 14 for engaging the straight rungs 13 and the double V shaped rung 11 to the chain 12 are placed over the links and the ends forced together into holes properly spaced in the rungs.

I claim as my invention:

30 35 In a flexible ladder comprising spaced chains, a rung made of strip material secured to said chains and having its end portions bent to form rearward, V-shaped spacer elements having their free ends secured to the chains of the ladder.

PARK LESTER NEWBOLD.
